[57] CLAIM

The ornamental design for cartridge for a label printer, as shown and described.

DESCRIPTION

FIG. 1 is a front elevational view of cartridge for a label printer, showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a rear elevational view thereof;

FIG. 7 is a front, bottom and left side perspective view thereof; and,

FIG. 8 is an exploded perspective view thereof.

The broken lines are for illustrative purposes only and form no part of the claimed design.
